RECONDITIONING APPARATUS FOR
DOFFER ASSEMBLIESCarl R. Worthington, Tulare, Calif., assignor of
one-half to Corcoran Implement Company, Inc.,
Corcoran, Calif.

Application May 18, 1953, Serial No. 355,822

5 Claims. (Cl. 51—55)

1

The present invention relates to tools for mechanical cotton pickers and more particularly to a reconditioning apparatus for the doffer assemblies of such pickers.

In mechanical cotton pickers, it is the usual practice to motivate barbed picking spindles through circuitous paths successively through a picking station in the machine and a doffing station. The spindles are arranged in vertically spaced sets, with the spindles of each set traveled in the same path and continuously rotated in a predetermined direction. Such pickers are motivated in earth traversing movement along rows of cotton so that the plants successively pass through the picking station of the machine and are deprived of their cotton by the spindles.

It is necessary to remove the cotton from the spindles at the doffing station so that upon return to the picking station their action can again be effective. This is accomplished by doffer plates or disks individually adjacent to the spindles rotated at such speed and in sufficient proximity to their respective spindles so as to unwind cotton from the spindles while their rotation continues. Obviously the doffer plates must rotate at a speed considerably in excess of the speed of spindle rotation and in a direction traveled in the same direction as the barbs of the spindle to unwind the cotton.

The doffer plates are usually metal and have rubber or other suitable doffing material vulcanized or otherwise secured thereto and provide pads extended therefrom. The spacing of the pads relative to the barbs of the spindles is critical and any substantial variation causes the barbs to strike the pads, usually damaging both the pads and spindles, or to be so excessively spaced therefrom as to fail to remove picked cotton from the spindles. The latter precludes effective picking and frequently results in excessive cotton accumulation on the spindles with jamming and serious damage to the picker mechanism.

One of the major expenses in the maintenance of cotton pickers is the reconditioning of doffer assemblies to avoid the difficulties discussed. It is known to grind the pads of the doffer plates so as to recondition damaged surfaces thereof. It is also a frequent practice to replace the damaged plates with new plates. Both procedures have proved objectionably expensive because of the numerous plates employed in each picker. Of greater consequence, are the difficulties incident to the proper spacing of the doffer plates for proper coaction with their respective spindles. This has proved a tedious, time consuming, and expensive task rarely performed with the precision desired. The usual practice is to endeavor to achieve desired spacing by inserting shims between adjacent doffer plates and measuring re-

2

sultant doffer pad spacing against spindle requirements. This is essentially a trial and error procedure which is entirely unsatisfactory but which represents the currently tolerated practice.

An object of the present invention is, therefore, to provide an improved doffer assembly reconditioning apparatus operable effectively on new and used doffer plates precisely to space working surfaces thereof.

Another object is to provide such an apparatus which is suitable for resurfacing used doffer plates to return the same to efficient operating condition.

Another object is to provide a reconditioning apparatus for doffer assemblies in which such assemblies can be quickly and easily mounted for rotation and removed.

Another object is to provide such an apparatus in which a grinder is speedily and easily located for successive doffer plate engagement with such precision that subsequent to grinding of the plates they present working surfaces in predetermined spaced relation suited to coaction with picking spindles in mechanical cotton pickers without further adjustment or measurement.

Further objects and advantages are to provide improved elements and arrangements thereof in a device of the character and for the purposes set forth.

Still further objects and advantages will become apparent in the subsequent description in the specification.

In the drawings:

Fig. 1 is a plan view of an apparatus embodying the principles of the present invention showing a conventional doffer assembly mounted therein for reconditioning purposes.

Fig. 2 is a fragmentary front elevation of the apparatus having a portion of its supporting frame broken away for illustrative convenience.

Fig. 3 is an end view of the apparatus, as viewed from the right end of Fig. 2.

Fig. 4 is a fragmentary vertical transverse section through the apparatus taken on line 4—4 in Fig. 2.

Fig. 5 is a fragmentary vertical transverse section through the apparatus, as taken on line 5—5 in Fig. 2 of the drawings.

Fig. 6 is an enlarged fragmentary section taken on line 6—6 in Fig. 1.

Fig. 7 is an enlarged fragmentary section taken on line 7—7 in Fig. 4.

Referring in greater detail to the drawings:

The apparatus of the present invention, indicated generally by the reference numeral 10, is adapted to recondition cotton picker doffer assemblies of the character shown at 11.

The doffer assembly 11 is of conventional construction and is normally employed in connection with barbed spindles of mechanical cotton

picker to remove cotton therefrom. The doffer assembly consists of an elongated spindle 15 having a plurality of circular disks 16 located therealong in equally spaced concentric relation normal to the spindle. Faces of the disks disposed in a common direction have rubber vulcanized thereto providing annularly arranged, radially elongated pads 17. One end of the shaft 15 is provided with an endwardly extended journal 18 and its opposite end is provided with a head 19.

The apparatus 10 provides a substantially rectangular frame 22 fabricated from angle iron or the like including four vertical legs 23, longitudinal horizontal side braces 24 rigidly interconnecting the legs and transverse end pieces 25 rigidly interconnecting legs at opposite ends of the longitudinal members. A head plate 28 is mounted between the upwardly extended legs at one end of the frame and a tail plate 29 mounted between the upwardly extended legs at the opposite end of the frame. The mounting plates 28 and 29 are conveniently attached to their respective legs by means of bolts 30. A rod 31 interconnects the mounting plates in fixed spaced relation adjacent to a side of the frame, herein-after referred to as the "forward side." A substantially rectangular bed plate 32 is connected to the mounting plates 28 and 29 by bolts 33 and extends substantially horizontally therebetween in parallel spaced relation to the rod.

The doffer assembly 11 is rotatably mounted in the frame of the apparatus by providing a bracket 38 attached to the bed plate 32 adjacent to the head plate 28. A bearing 39 is mounted in the bracket and rotatably receives the journal 18 of a doffer assembly. A bearing 40 is mounted on the tail plate 29 and has a drive shaft 41 rotatably mounted therein longitudinally of the frame. The drive shaft provides an inner end having a circular flange mounted concentrically thereon. The doffer shaft 15 is releasably connected in axial alignment with the drive shaft by a plurality of bolts 43 passed through the flange and screw-threadably tightened into the head 19. A pulley 44 is secured to the outer end of the drive shaft.

A rectangular shelf 48 is hinged at one of its edges to one of the longitudinal side braces 24 of the frame 22 and substantially horizontally extended beneath the bed plate 32. An electric motor 50 having a reduction drive box 51 is mounted on the shelf and provides a drive pulley 52 endwardly of the frame. A belt 53 is extended around the pulleys 44 and 52. For clutching purposes, a lever 54 is welded at one of its ends to the shelf 48 and extended upwardly and thence forwardly therefrom beyond the frame of the machine. The extended end of this lever is guided in vertical pivotal movement against one of the legs 23 of the frame by an inverted L-shaped guide 55 attached to the leg and having an arm downwardly extended in substantially parallel relation thereto. Downward movement of the shelf and the members mounted thereon is ordinarily limited to the extent permitted by the belt 53 around the pulleys 44 and 52, but excessive lowering of the shelf, as in the event the belt is broken, is limited by a pin 56 extended outwardly from the leg 23 downwardly adjacent to the guide. The lever may be lifted to slacken the belt 53 when it is desired to interrupt rotation of the drive shaft 41 and the doffer assembly 11. A ratchet-shaped keeper 57 is inwardly extended from the guide and provides a releasable rest for the lever.

An elongated index bar 62 having a plurality of circumscribing, inwardly tapered grooves 63 formed therein is mounted between the plates 28 and 29 in parallel elevationally spaced relation to the rod 31. As most evident in Figs. 1 and 2, the grooves are equally spaced longitudinally of the index bar increments equal to the desired spacing of the corresponding faces of the pads of the doffers 16 subsequent to reconditioning.

In order to obtain endward adjustment of the index bar, one end of the bar is slidably supported in a split sleeve 64 secured to the inner face of the tail mounting plate 29. A T-bolt 65 is extended across the split portion of the sleeve and, as shown in Fig. 1, has an extended end screw-threadably mounted in one portion of the sleeve with a circumscribing collar engaged with the opposite portion thereof whereby tightening of the bolt clamps the index bar in the sleeve. The index bar is longitudinally adjustably positioned minutely and accurately by an adjusting means 66. The adjusting means comprises a hollow thimble 67 having a closed end 68 rigidly attached to the head mounting plate 28. A screw 69 is extended longitudinally through the thimble and has an inner end screw-threaded into an opening 70 formed endwardly into the adjacent end of the index bar. The screw 69 has an enlarged flange 71 which engages the inner side of the closed end of the thimble. The screw extends through a bore 72 in the closed end of the thimble and is of reduced diameter at 73 exteriorly of the thimble. A knurled knob 74 slips over the reduced diameter of the screw with a nut 75 threaded onto the screw against the knob so that the screw and knob are rotatable unitarily. With the T-bolt 65 loosened, its end of the index bar is free to slide endwardly in the sleeve. The index bar may then be adjustably endwardly positioned by rotation of the screw 69 by the knurled knob 74. Once the desired adjustment is obtained it is maintained by tightening the T-bolt 65 and clamping the sleeve against the index bar.

Work is performed on the pads of the doffer assembly by a grinder 80 mounted on a support 81 having a cylindrical opening 82 therethrough which slidably and rotatably fits the index bar. The support extends upwardly from the index bar and has a bore 83 formed through its extended portion in axially parallel relation to the index bar. A grinder spindle 84 is rotatably supported in the bore 83 with a grinding wheel 85 attached concentrically to one of its ends and a pulley 86 similarly secured to its opposite end. The upper portion of the support and the grinding wheel thereon are movable toward and away from the doffer assembly by pivoting of the support by manual manipulation of a handle 87 extended forwardly from the support. A motor mounting plate 88 extends downwardly from the support 81. A motor 89 having a driving pulley 90 is attached to the rear side of the motor mounting plate. A belt 91 extends circuitously around the pulleys 86 and 90 whereby the grinding wheel is rotated by operation of the motor 89. For reasons soon to become apparent, the grinding wheel and the motor are located in substantially diametrically oppositely spaced relation to the index bar 62. The grinding wheel 85 is adjustably positionable along the index bar to precise predetermined positions for grinding the faces of the pads 17 on the disks 30 to their proper uniform spacing. For this purpose a

sleeve 96 extends endwardly from the support 81 and the cylindrical opening 82 of the support also formed through the sleeve. A radial bore 97 is formed through the sleeve 96 and a riser 98 is attached radially of the sleeve by bolts 99 in a position over the bore 97. A central bore 100 is machined through the riser in alignment with the radial bore 97 in the sleeve, and a counterbore 101 formed in axial alignment therewith defining a shoulder 102 at the juncture of the bore 100 and the counterbore 101. An elongated detent pin 103 extends slidably into the central bore 101 and has a frusto-conical inner end 104 adapted to rest in the tapered grooves 63 in the index bar 62. The pin has an integral enlarged collar 105 thereon which rides in the counterbore 101. The pin is urged inwardly toward the index bar by a helical compression spring 106 located in the counterbore 101 between the collar 105 on the pin and cap 107 screwed on the outer end of the riser. A T-handle 108 at the outer end of the pin permits the manual withdrawing of the pin from seated engagement in any of the grooves 63 for repositioning purposes. The pin may be held in withdrawn position by providing a J-slot 109 in the riser and a latch pin 110 extended radially from the adjusting pin into the J-slot. After the adjusting pin is manually withdrawn from a groove, the pin is rotated to move the latch pin into the laterally extended portion of the slot. With the adjusting pin held in withdrawn position, the grinding wheel may be moved longitudinally of the index bar to any desired location therealong. On reverse rotation of the T-handle, the adjusting pin is released for return to any selected groove 63.

Operation.

The operation and utility of the present invention are believed to be apparent and are briefly summarized at this point. A doffer assembly 11 in need of servicing is placed in the apparatus by inserting its journal 18 into the bearing 39 in the bracket 38 and by attaching the head 19 thereof to the attaching disk 42 on the drive shaft 41 by means of the bolts 43. The motor 50 is then energized to rotate the doffer assembly. The index bar 62 is longitudinally adjusted in the frame and secured in position in the manner described. It will be recalled that the grooves 63 are spaced in precise conformance to the desired spacing of the operative faces of the pads 17 when mounted in a cotton picking machine.

The adjusting pin 103 is withdrawn from engagement with its groove 63 and preferably rotated so as to be held releasably in retracted position. The grinder 80 and its support 81 are then slid longitudinally of the index bar 62 until the pin is aligned with the endmost groove 63 adjacent to the head plate 29, as shown in Figs. 1 and 2. The pin is released and spring pressed into the groove whereupon the support 81 is held in fixed position longitudinally of the index bar but is rotatable on the index bar for movement of the grinder 80 toward and from the doffer assembly. So adjusted, the grinding wheel should be engageable with the pads 17 of the endmost disk 16 of the doffer assembly to remove a predetermined thickness of material therefrom. If not, the index bar is readjusted to desired position.

With the motor 39 rotating the grinder 80, the grinding wheel 85 is brought into engagement with the pads 17 of the disk 16 rotated adjacent thereto by rotating or pivoting the support 81 on the index bar. The engagement of the pin

103 in its groove 63 maintains the grinding wheel in fixed position longitudinally of the doffer assembly 11 during such pivotal movement. The grinding wheel at all times is rotated in a plane normal to the axis of the doffer assembly and the side thereof grinds the pads 17 so that the working surfaces thereof are disposed in a common plane normal to the axis of rotation of the doffer assembly.

When the pads 17 on the first disk are thus reconditioned, the pin 103 is withdrawn from the groove 63 and the support 81 slid longitudinally of index bar 62 until the pin is aligned with the next groove. The pin is released for engagement in said next groove, precisely positioning the support 81 and grinder 80 for operation on the pads 17 of the adjacent disk 16.

Upon completion of the grinding action on successive doffer disks, the doffer assembly is released from the apparatus by removing the bolts 43 and withdrawing the journal 18 from the bearing 39. The doffer assembly can then be reinstalled in its cotton picker with perfect assurance that the doffing surfaces of the pads are properly spaced for coaction with their respective picking spindles. This is true whether the doffer disks ground by the apparatus are new or used. Whatever axial adjustments of the doffer assembly in the picker may be found desirable, the assembly automatically correspondingly positions all of the disks 16 and their respective pads.

The motor 39 and the grinder 80 are mounted on the support 81 so that they are balanced on the index bar 62 in approximate position shown in Fig. 4. Thus, when the handle 87 is released by an operator, the grinder is retracted from the doffer assembly. The balance is such, however, that the grinder is moved inwardly of the rotated doffer assembly easily and without fatigue by lifting upwardly on the handle. Similarly, movement longitudinally of the index bar is effected by an operator having one hand grasping the handle and the other grasping the pin 103 to release the same.

Rotation of the doffer assembly 11 is conveniently interrupted by raising the lever 54. If it is desired to interrupt such rotation for an appreciable period of time, the lever is normally rested on the keeper 57. To renew rotation, the lever is released for gravitational return to the pin 56 whereupon the belt 53 is tightened into driving interconnection of the pulleys 44 and 52.

The apparatus of the present invention has substantially reduced the cost and increased the speed of reconditioning doffer assemblies. The reconditioned doffer assemblies are superior to those hereofore attained particularly in the precision of spacing of the working surfaces of the pads 17.

Although the invention has been herein shown and described in what is conceived to be the most practical and preferred embodiment, it is recognized that departures may be made therefrom within the scope of the invention, which is not to be limited to the details disclosed herein but is to be accorded the full scope of the claims so as to embrace any and all equivalent devices and apparatus.

Having described my invention, what I claim as new and desire to secure by Letters Patent is:

1. A doffer assembly reconditioning apparatus comprising a frame, means in the frame adapted releasably to mount a doffer assembly therein for rotation in a predetermined position, an index

bar mounted in the frame in substantially parallel relation to the position for the doffer assembly, said bar having circumscribing grooves in substantially equally spaced relation therewith, a support member pivotally mounted on the index bar for slidable movement longitudinally thereof, a power driven grinder mounted on the support member for doffer assembly engagement, and means borne by the support member for engagement in the grooves of the index bar releasably to retain the support member in fixed position longitudinally of the index bar and slidable in the grooves to accommodate pivotal movement of the support member while retained in said fixed longitudinal position.

2. In a doffer assembly reconditioning apparatus, a frame, an elongated index bar having circumscribing grooves therein in substantially equally spaced relation longitudinally thereof, means mounting the index bar in a substantially horizontal position in the frame for adjustable longitudinal movement, a support member rotatably mounted on the index bar, a detent pin mounted for longitudinal slidable movement on the support member radially of the index bar, resilient means urging the pin toward the bar for engagement in the grooves releasably to retain the support member in adjusted position longitudinally of the bar while accommodating rotatable movement of the support member on the bar, a grinder mounted on the support member eccentrically of the index bar, and means for rotatably mounting a doffer assembly in the frame in substantially parallel relation to the index bar for engagement therewith by the grinder.

3. A doffer assembly reconditioning apparatus comprising a support frame, means in the frame adapted to mount a doffer assembly in predetermined horizontal position for rotation about an axis concentric thereto, a shelf pivotally mounted in the frame beneath the mounting means for movement about an axis substantially parallel to the doffer assembly's axis of rotation, a pulley on the mounting means, a motor mounted on the shelf having a pulley aligned with the pulley on the mounting means, a belt circumscribing the pulleys and supporting the motor and the shelf on the mounting means, an index bar mounted in the frame in substantially parallel relation to the mounting means, said bar having circumscribing annular grooves in substantially equally spaced relation longitudinally of the bar, a support member rotatably and slidably mounted on the bar, a power driven grinder mounted on the support member eccentrically of the bar for engagement with doffer assemblies mounted in the mounting means, and detent means borne by the support member engageable with the grooves of the bar releasably to retain the support member in fixed position longitudinally of the bar while accommodating rotatable positioning of the support member on the bar.

4. In a doffer assembly reconditioning apparatus, a frame having substantially parallel end plates providing horizontally aligned openings therethrough, a split sleeve mounted in substantially horizontal position on one of the plates in registry with the opening therein, a substantially cylindrical thimble rigidly mounted in axial alignment with the sleeve in the opening of the plate opposite to the plate mounting the sleeve, said thimble having an open end disposed toward the sleeve and an opposite closed end having a bore concentrically therethrough, a screw rotatably mounted in the bore of the thimble in fixed

axial relation to the thimble and extended longitudinally thereof toward the sleeve, an index bar having an end slidably mounted in the sleeve and an opposite end slidably mounted in the thimble providing a co-axially disposed bore having the screw screw-threadably mounted therein for longitudinal positioning of the bar relative to the thimble, means for constricting the sleeve about the bar to secure the bar in adjusted longitudinal position, said bar having a plurality of circumscribing grooves located in planes normal to the bar substantially equally spaced longitudinally of the bar, each of the grooves having convergent side walls inwardly of the bar, a support member pivotally mounted on the bar for slidable movement longitudinally thereof, a detent pin mounted for reciprocal longitudinal movement in the support member radially of the index bar having a frusto-conical inner end engageable with the convergent side walls of the grooves releasably to retain the support member in adjusted position longitudinally of the bar while accommodating pivotal movement of the support member by slidabale movement of the pin in the grooves, resilient means urging the pin toward the bar, a power driven grinder mounted on the support member having a grinding wheel rotated about an axis substantially parallel to the bar, and means for releasably mounting doffer assemblies in the frame in parallel relation to the bar for engagement by the grinding wheel.

5. A doffer assembly reconditioning apparatus comprising a support frame, means in the frame adapted to mount a doffer assembly in predetermined horizontal position in the frame for rotation about an axis concentric thereto, driving means connected to the mounting means for rotating such doffer assembly, an elongated index bar mounted in the frame in parallel relation to the axis of rotation of doffer assembly in the frame, the index bar having circumscribing grooves therein in substantially equally spaced relation longitudinally thereof, each located in a plane normal to the index bar and having inwardly convergent side walls, means interconnecting the index bar and the frame longitudinally adjustably positioning the bar in the frame, a support member mounted on the index bar for adjustable slidable movement longitudinally thereof and rotatable positioning thereon, a grinder mounted on the support having a grinding wheel rotatable in a plane normal to the axis of rotation of the doffer assembly, a motor mounted on the support having driving connection to the grinder, the motor and the grinder being so positioned on the support member as to balance on the index bar with the motor therebelow and the grinder thereabove disposed adjacent to the predetermined position for the doffer assembly, a handle extended from the support member whereby the support member may be rotated on the index bar to move the grinding wheel to and from doffer assembly engagement, an elongated detent pin mounted for longitudinal slidable movement on the support member radially of the index bar having a frusto-conical inner end slidably fitted to the convergent side walls of the grooves, and resilient means urging the pin toward the index bar for position controlling engagement in the grooves while the support member is rotatably positioned on the index bar.
